WEB TENSION CONTROL

Frank J. Wood, Spokane, Wash., assignor to
Erwin Loewy, New York, N. Y.

Application June 29, 1950, Serial No. 171,170

4 Claims. (Cl. 242—75)

1

This invention relates to an apparatus for holding and controlling the feeding of sheet material and is especially suitable for feeding material to rolling mills for thin foil and the like.

It has been difficult in the prior art to properly control the unwinding of sheet foil, particularly very thin foil, and also to prevent backlash in the unwinding apparatus. Another problem has been the provision of a suitable chuck for holding the sheet material reels or spools. It is desirable to be able to slip the spool over the chuck and then to clamp the spool in place on the chuck.

One of the objects of the invention is to provide an improved apparatus for controlling the feed or unreeling of sheet material.

A further object is to control the position of the material being unreeled, such as in a doubling and slitting operation.

One of the features of the invention is the use of a means employing an electric apparatus for applying a braking force to the reel as the sheet material is fed to a rolling mill or the like. In conjunction therewith, a free wheeling clutch arrangement may be connected to the mechanism controlling the rotation of the reel by preventing movement thereof in a direction reversed relative to the unreeling rotation for the purpose of preventing backlash or backward rotation in the event the foil breaks.

These and other advantages, features, and objects of the invention will become apparent from the following description and drawings.

In the drawings:

Figure 1 is a fragmentary plan view partially in section.

Figure 2 is an enlarged elevation taken along the line 2—2 of Figure 1.

Figure 3 is an enlarged fragmentary view, partially in section, taken along the line 3—3 of Figure 1.

Figure 4 is a fragmentary view, partially in section showing the upper half of the chuck mechanism of Figure 1 in released position.

Figure 5 is a schematic side view of one form of a doubling combination in which the invention can be used.

Figure 6 is a plan view of Figure 5.

As mentioned, the apparatus is particularly useful for holding a reel of sheet material so as to feed it properly to an apparatus such as a rolling mill or the like, or in conjunction with a doubling arrangement. In the feed of material to an apparatus, such as a rolling mill, particularly when thin foil is involved, it is desirable to place

2

a continuous tension on the sheet material. It also is necessary to prevent movement in a backward direction in the event the strip being fed or unreeled should slow up or break.

5 Frame 10 of the device supports gearing connected with electric motor 11. The frame 10 also supports the chuck arrangement generally indicated at 12 and the backlash preventer 13. Electric motor 11 is connected through shaft 14 with small pinion 15, said pinion engaging gear 16. Gear 16 is supported on shaft 17 which is held in bearings 18 and 19 on frame 10 of the mechanism. Gear 16 meshes with gear 20, gear 20 being keyed to sleeve 21 by key 22. Sleeve 21 is rotatable in bearings 23 and 24 carried by frame 10 of the machine.

The reciprocable chuck assembly shaft 25 is longitudinally movable within the bore of sleeve 21, said reciprocable shaft 25 being keyed by 20 some suitable means to sleeve 21. The reciprocable shaft 25 is arranged so that it can have the desired predetermined longitudinal movement relative to sleeve 21, sleeve 21 being fixed longitudinally relative to frame 10. Reciprocable shaft 25 has a tail piece 26 (Fig. 2) rotatably mounted at 27 in frame 28. Tail piece 26 has a collar 29 thereon so as to be held longitudinally relative to said reciprocable frame 28. Frame 28 can have a lug 30 depending therefrom with a nut 31 fastened thereto, nut 31 being engageable with rotatable threaded adjusting rod 32. The adjusting rod 32 can have a worm wheel 33 mounted thereon, said worm wheel 33 being rotatable by worm 34 drivable by motor 35. Upon operation of motor 35 in either direction, the resultant rotation of adjusting rod 32 will cause a movement of frame 28 so as to move the reciprocable shaft 25 to the right or left as desired and this will serve to properly position chuck assembly 12 and reel 36 relative to the machine to which strip from reel 36 is being fed. As will be explained hereafter, such movement can be controlled automatically.

As will be explained hereafter, when shaft 44 is moved to the left by motor 48, jaws 39 will be moved outwardly because of movement of slide 81 to the left. During this time, abutment 43 will urge jaws 39 against inturned ends 84C. After lugs 82A have moved far enough to pass the ends 84C, lugs 82A will engage the right-hand (Fig. 4) face of jaws 39, so that further movement of the shaft 44 will move the jaws to the left toward flange 38 of the spindle. Thus, the jaws first are moved outwardly and then 50 are moved longitudinally by the continuous axial

movement of shaft 44 so as to engage a coil between jaws 39 and inclined surface or flange 38.

Motor 11 can be connected electrically so as to provide a braking force on the reel 36 as the material is unrolled and the amount of braking action can be adjusted in any suitable manner.

If power is supplied to the motor tending to rotate it in a direction opposite to the unreeling direction, the roll 36 will be rotated in the opposite direction in the event of breakage of the foil. In order to prevent such counterrotation of roll 36, an automatic clutch or brake means 53 can be provided.

Gear 49 is keyed to sleeve 21 by key 50. Gear 49 meshes with gear 51, said gear 51 being mounted on shaft 52. Free wheeling clutch 53 has an inner cam unit 54 (Fig. 3) mounted on shaft 52. Cam unit 54 has indentations 55 therein with sloping faces as shown. Rolls 56 are carried between cam unit 54 and the outer race or sleeve 51, 20 outer race 51 being mounted on or carried by an upright stationary member 58 so that the outer race is held stationary relative to the frame of the machine. The motor is arranged so that when the reel is feeding material to the rolling mill, shaft 52 will rotate in the direction indicated by the arrow in Figure 3, the balls being carried along by the radial portions 59 of the cam unit 54. The cam unit 54 can be reversed or arranged according to the direction in which reel 36 is to be rotated freely. In the event shaft 52 should reverse its direction, then the balls will slide along and outwardly on the sloping faces 55 of the indentations and thus stop the mechanism from being rotated in the wrong direction by motor 11 or otherwise.

Automatic positioning of the reel relative to the mill to which material is being fed can be accomplished in various manners. One example is illustrated in Figures 5 and 6 wherein two of the devices are used in conjunction with a doubling arrangement, wherein it is necessary to accurately align the edges of the sheets. Identical parts are given the same reference characters in Figures 5 and 6 as in the preceding figures.

Prior practice has been to take two coils after they have been rolled to a certain thickness and put them on a machine known as a "Slitter Doubler." After they have been slit, doubled, and rewound, the strip is annealed and sent to the mill for further reduction. Thus, two separate machines and operations have been required. Also, increased coil size makes for a greater differential of build-up of coil diameter during the operation. To match two strips, they must be kept under reasonably constant tension so that they will wind uniformly after being rolled together.

A rolling mill is indicated at 59 of the four high-type having two working rolls 51, 54 and backing rolls 52, 52. A guide roll 53 can be fastened on one side of the mill so as to guide the material into the rolls. The coils 36A, 36B of sheet material may be mounted on the unwinding chucks or spindles 31A, 31B, said coils of sheet material being held on said chucks in axially fixed positions, the chucks themselves being movable axially so as to position the edge of the sheet.

The sheet material from a full roll 36A is indicated at 58, being fed thereto by guide roll 59. Similarly, the sheet material 60 from roll 36B is fed under guide roll 61. Guide rolls 59 and 61

extend longitudinally of the frame 62 of the slitting and positioning apparatus.

The two sheets of material are fed from guide rolls 59 and 60 to the doubling roll 63 where the sheets are brought into contact with each other.

The sheets are fed from doubling roll 63 to the slitter guide roll 64, and thence to the feed roll 65.

A slitter or trimmer is located at 66 for the purpose of trimming the edges of the two sheets, the slitter being adjustable lengthwise of the slitting and positioning apparatus 62.

The sheets are fed to said roll 65 and then to the rolling mill 50. A rewind reel 66A is at the far end of the rolling mill for receiving the rolled doubled material thereon, said rewinding coil being rotated by a suitable motor apparatus (not shown). The trimmings from the sheets may be gathered in trough 67 and drawn out by blower arrangement 68 to a disposal point.

In order to position the sheets axially and in correct position relative to each other, a photo-electric control arrangement for the upper sheet is seen at 69 and a photo-electric positioning means for the lower sheet at 70. The photo-electric positioning apparatus may have an electric-eye arrangement scanning the edge of the sheet for the purpose of operating the control devices connected with the motors 35 of the unwinding machines for properly positioning the edge of the sheets. As is known in the art, the photo-electric cell control will produce a control signal indicating the deviation of the edge of the moving web as to direction and amount from the desired position and this is used to operate motors 35 (Fig. 6), to adjust the position of the edge of the sheets. It is thus apparent that a mechanism can be provided wherein sheet material can be unwound at high speeds, doubled, slit and then fed to a rolling mill without the necessity of having intermediate winding and unwinding devices. Other control means than photo-electric can be used, such as mechanical feelers. Two or more strips of sheet material can be payed-off from laterally adjustable braked reel heads, the strips being matched, slit, and fed to a rolling mill or the like.

The chuck is arranged so that the reel spool can be slipped thereover and a single operator used to move the jaws into radial gripping engagement with the spool and then to move the spool axially relative to the chuck so as to clamp it between said jaws and a fixed sloping collar or surface on the chuck spindle.

As mentioned previously, reciprocable shaft 44 having an extension 45 is connected to and operable by hydraulic motor 48. Shaft 44 has a shoulder 44A against which the jaw slide member 81 is held by cap 82 and nut 83. Jaw slide 80 has a plurality of longitudinally extending sloping slideways in which jaws 39 are slideable. Chuck spindle 84, which can be integral with tube 25 has an enlarged bore therein receiving spring 40 and providing an abutment for one end thereof. A still further enlarged bore 84A receives the jaw abutment member 43. The chuck spindle 84 has a plurality of longitudinally extending slots 84B (Fig. 4) therein, there being in-turned lugs 84C at the ends thereof for holding the jaws 39 between the lugs and the spring pressed abutment member 43. The transverse width between the lug faces 84C is made such that lugs 82A of the cap 82 can enter and come into engagement with the right hand surfaces of the jaws. The lugs are made a transverse width such

that they will enter between the inturned lugs 84C.

The parts are shown in their inactive position in Figure 4. As the shaft 44 is moved to the left, the jaws will be held in their right hand position abutting lugs 84C until lugs 82A reach the jaws, at which time the jaws will be in their radially extended position. Further movement of the shaft 44 to the left will cause movement of the jaws to the left to the position illustrated in Figure 1, so as to tightly clamp spool 37 between the jaws and the sloping shoulder 38. A schematic showing of the control circuits for the motors 35 and photo-cells 69 and 70 is illustrated by the wires C, D and E being connected to the control box.

The term "foil" in the claims is meant to include strip, foil normally meaning in the art relatively thin strip.

It is to be understood that the apparatus can be used for various purposes and that changes may be made in the details of construction without departing from the spirit of the invention except as defined in the appended claims.

What is claimed is:

1. In a foil unwinding machine, the combination comprising a reel spindle, a sleeve means carrying said spindle, said spindle being longitudinally moveable relative to said sleeve so that the spindle can be selectively positioned, a rotatable electric braking means connected to said sleeve means placing tension on strip being unreeled from said spindle, and a free-wheeling braking means connected to said sleeve means freely rotatable when the sleeve and spindle are rotating in unreeling direction, but automatically moving to a braking position if rotation of said reel is reversed from its unreeling condition so as to prevent backlash and the like.

2. In a foil unwinding machine, the combination comprising a reel spindle, a rotatable electric motor connected to said reel spindle through a power transmission means for applying a braking force to said spindle as it rotates in an unreeling direction, and a braking clutch connected to said power transmission means, said clutch having cam means thereon stopping rotation of said spindle if movement of said power transmission means from other than an unreeling direction takes place.

3. In a foil unwinding machine, the combination comprising a reel spindle, a rotatable elec-

tric motor connected to said reel spindle through a power transmission system for applying a braking force to said spindle as it rotates in an unreeling direction, and a braking clutch connected to said power transmission system and thus to said spindle, said clutch having a sleeve and cam unit inside of said sleeve, said sleeve and cam unit being freely rotatable relative to each other when the spindle is turning in an unreeling direction, said cam unit having sloping surfaces and rolling elements between said sloping surfaces and sleeve, so that if the spindle moves in a direction the reverse of unreeling, the rolling elements will move outwardly on the sloping surfaces to stop the spindle.

4. In a foil unwinding machine, the combination comprising a sleeve, a reel spindle element slidably mounted in said sleeve and rotatable therewith, said element being moveable to change the position of a reel thereon relative to said sleeve, a gear train connected to said sleeve, means adapted to connect a rotatable electric motor to said gear train for tensioning foil being unwound from said spindle, a second gear train connected to said sleeve, and a braking clutch connected to said second gear train, said braking clutch having a fixed collar and a cam unit inside of said collar, said collar and cam unit being freely rotatable relative to each other when the spindle is turning in an unreeling direction, said cam unit having sloping surfaces and rolling elements between said sloping surfaces and collar, so that if said spindle starts to rotate in a direction the reverse of unreeling, the rolling elements will cooperate with said sloping surfaces to stop the spindle.
